Attorney.

UNITED STATES PATENT OFFICE.

JOHN W. WEAVER, OF DETROIT, MICHIGAN, ASSIGNOR OF ONE-HALF TO BUFORD A. LYNCH, OF WASHINGTON, DISTRICT OF COLUMBIA.

AIR-VALVE FOR GASOLENE-ENGINES.

1,252,972.

Specification of Letters Patent. Patented Jan. 3, 1918.

Application filed June 11, 1917. Serial No. 174,123.

To all whom it may concern:

Be it known that I, JOHN W. WEAVER, a citizen of the United States, residing at Detroit, in the county of Wayne and State of Michigan, have invented Air-Valves for Gasolene-Engines, of which the following is a full and complete specification.

My invention is an improvement in valves of that particular class which are applied to the manifold intake pipe of gasoline engines and operate automatically to open and furnish an additional supply of air to the mixture of vaporized gasoline when the engine is running at high speed, to effect a saving in the consumption of gasoline.

The primary object of my invention is to provide an air-valve of this general character which may be readily and conveniently applied, and will be regular and positive in its operation.

A further object of my invention is to provide a valve mechanism of such construction that the valve is practically closed when the engine is at rest, will completely close at low engine speed, and will open to its maximum capacity when the engine attains and exceeds a predetermined high speed; to thereby insure the proper running of the engine at different speeds.

Other objects and advantages of my invention will hereinafter appear, and what I particularly claim as new, and desire to protect by Letters-Patent, is more specifically set forth in the appended claims.

In the accompanying drawings, forming a part hereof:—

Figure 1 is an elevation illustrating the application of my invention.

Fig. 2 is a side view of the valve, and including an attachment by which it may be conveniently applied to the intake manifold pipe at its junction with the carburetor.

Fig. 3 is a sectional view of the valve in open position.

Fig. 4 is a similar view of the valve in closed position.

Figs. 5 and 6 are sectional views on the lines 5—5 and 6—6, respectively, of Fig. 4.

Fig. 7 is a sectional view of the valve, showing a modification, and

Fig. 8 is a sectional view on the line 8—8 of Fig. 7.

Like numerals of reference indicate like parts in all the figures of the drawings.

In carrying out my invention I employ

a straight coupling 10, into which the tubular valve-casing 11 is threaded to a more or less extent, being held in adjustment with respect to said coupling, for the purpose hereinafter explained, by means of a check-nut or milled binding ring 12, threaded on the valve-casing to impinge against the end of the coupling. The tubular valve-casing is reamed out from its inner end for some distance to provide a bore 13 slightly larger than the bore 14 at the outer end portion, and forming also a stop-shoulder 15 where one bore joins the other.

Working slidably and loosely in the bore 14 of the aforesaid valve-casing is a plug 16 having a flanged cap 17 at its outer end and at its inner end connected by a stem 18 to a disk 19 working in the larger bore 13; the construction and arrangement of these parts being such that when the disk or piston 19 strikes against the shoulder 15 the plug will project a short distance beyond the outer end of the valve-casing, and, conversely, when the plug is moved inward the flanged cap will close tightly against the end of said casing. Air is admitted into the valve, through the plug, by means of L-shape ports 20, entrance being immediately below the cap and exit at the inner end of said plug adjoining the stem. Four of these ports 20 are preferably provided, as indicated in the drawings, but the number may be increased or diminished, or the size of said ports varied, according to the amount of air the valve is designed to supply. Ports 21 are also provided through the disk or piston 19, so that when the valve is in open position, (as shown in Fig. 3), air may pass through the valve to the coupling and into the manifold intake pipe, 25, as hereinafter more fully explained.

The valve is held normally open by means of a helical spring 22 interposed between the disk or piston 19 and a shoulder 27 formed in the coupling, the tension of the spring 22 being such that the valve will close automatically when there is sufficient suction through the valve—caused by the rush of vapor through the intake pipe 25—to overcome the power of said spring. To vary the closing action of the valve, with respect to the suction from the intake pipe, the tension of the spring may be regulated by first unscrewing the check-nut 12 and then turning the valve-casing either way—screwing

it in to increase the tension of said spring or out to reduce it.

In order to prevent dust or other particles from passing to the engine through the air-valve I place a screen 23 in the coupling 10, seating it upon the shoulder 27, the latter being formed, as will be noted, by reason of the threaded bore 28 which receives the inner end of the valve-casing being 10 larger than the bore 29 leading to the intake pipe.

For convenience in fitting the plug and piston in the valve-casing the flanged cap 17 may be made separately and subsequently 15 secured to the plug, as shown in Fig. 3, or the disk 19 made separately and similarly attached, as shown in Fig. 7, the latter construction being required when the additional feature is used forming the modification 20 which I shall now describe. In this modification I employ an auxiliary valve device in the form of a washer 30 mounted to work on the stem 18 and almost completely close the inner ends of the ports 20 through 25 the valve-plug 16, said washer or disk-valve being moved to normally closed position against the inner end of the plug by means of a light helical spring 31 interposed between the same and the piston 19. The 30 spring is light in order to permit the said valve to unseat when there is a light current of air through the ports 20, and close when the engine is at rest, or when there is very little suction; the utility of this device being 35 hereinafter more fully explained.

The air supply valve hereinbefore described may be applied to the manifold intake pipe 25 at any point between the carbureter 32 and branches 25^a, 25^b of said intake pipe leading to the engine-cylinders, by simply tapping said pipe to receive the coupling 10; but I prefer to make the connection by means of a plate 33 adapted to be readily inserted between the lower 45 flanged end 25^b of the intake-pipe 25 and the corresponding connection flange 34 on the carbureter, for which purpose said plate is provided with apertures 33^a to receive the attaching-bolts 35, and with a tubular projection 36 threaded internally to receive the coupling 10. The attaching-plate is provided with a central opening corresponding 50 with the bore of the intake pipe 25, and into this opening leads a passage 37 communicating with the coupling.

It will be understood, of course, that any type of carbureter may be used, that herein shown being merely a conventional type employed for illustrating the application of 60 my invention which relates to the air valve mechanism.

In the operation of my improved valve it remains open (Fig. 3) until the suction caused by running the engine creates a rush 65 of air through the ports 20, and this air

striking against the piston 19 on its way to the ports 21 will close the valve (Fig. 4) when it is of sufficient force to overcome the strength of the spring 22, the valve again opening when the suction is reduced 70 in intensity. In the use of the valve it is found that it will close when the engine is running at a comparatively low speed, and will open and remain open when the engine attains a certain high speed and exceeds it; 75 whereby when the engine is running at high speed the inrush of the additional air through the valve will relieve the draft on the carbureter and thereby reduce the amount of gasolene fed from said carbureter, and this does not appear to affect the power of the engine, simply reducing the richness of the mixture at the proper time. Conversely, when the engine slows down the suction increases sufficiently to close the 80 valve and the usual mixture, for which the carbureter has been adjusted, is fed to the engine.

The form shown in Fig. 7 is particularly adapted for automobiles, particularly those 85 in which the engine is started manually by means of a crank or like contrivance. In this instance the disk-valve 30 maintains the valve practically closed, instead of fully open as shown in Fig. 3, so that in starting 90 the engine a rich mixture will be supplied through the manifold intake pipe, and when the engine begins running at low speed the suction will cause the plug 16^a to close, 95 after which, at high speed, the spring 22 100 will open the valve and the supply of air coming in through the valve will have to merely overcome the power of the light spring 31.

Having described my invention, I claim: 105

1. An air valve for the manifold intake of gasolene engines comprising a coupling, a tubular casing threaded therein, a plug working in the outer portion of the casing and provided with a flanged cap closing against 110 the end of said casing, said plug having openings leading through the same from the sides to the inner end, means for limiting the outward movement of the plug, and a spring acting to normally open the valve. 115

2. An air valve for the manifold intake of gasolene engines comprising a coupling, a tubular casing threaded therein, a plug working in the outer portion of the casing and provided with a flanged cap closing 120 against the end of said casing, said plug having openings through the same from the sides to the inner end, a piston connected to the inner end of the plug and having openings, and means for limiting the outward movement of the parts; together with a spring pressing against the piston to hold the valve normally open. 125

3. An air valve for the manifold intake of gasolene engines comprising a coupling, a 130

tubular casing threaded in an enlarged bore at one end thereof, a plug working in the outer portion of the casing and provided with a flanged cap closing against the end 5 of said casing, said plug having openings through the same from the sides to the inner end, a piston connected to the inner end of the plug and having openings through the same, means for limiting the outward movement of the plug and piston, a screen located 10 in the coupling, and a spring interposed between the screen and piston.

4. An air valve for the manifold intake

of gasoline engines comprising a coupling, a tubular casing threaded therein, a plug 15 working in the outer portion of the casing and having openings through the same, a piston located in said casing, a stem connecting the piston to the plug, a disk-valve on the stem to close against the inner end 20 of the plug over the openings therein, a spring pressing against the disk-valve, and a spring pressing against the inner end of the piston.

JOHN W. WEAVER.
